Filed Oct. 21, 1965, Ser. No. 87,725

Term of patent 14 years

U.S. Cl. D14—3

Int. Cl. D12—14

FIGURE 1 is a perspective view of an automobile hood showing my new design;

FIGURE 2 is a side elevational view thereof;

FIGURE 3 is a vertical sectional view taken substantially along the line 3—3 in FIGURE 2;

FIGURE 4 is a vertical sectional view taken substantially along the line 4—4 in FIGURE 2;

FIGURE 5 is a vertical sectional view taken substantially along the line 5—5 in FIGURE 2; and

FIGURE 6 is a side elevational view taken on a reduced scale.

The vehicle shown in broken lines in FIGURES 1 and 6 is included for illustrative purposes only.

The dominant features of the design reside in the portions shown in full lines.

I claim:

The ornamental design for an automobile hood, substantially as shown and described.
